UNITED STATES PATENT OFFICE

2,373,993

SMOKING APPLIANCE

Maurice Ben Brand, Chicago, Ill.

Application February 4, 1943, Serial No. 474,639

1 Claim. (Cl. 191—202)

The appliance of the present invention is designed as an attachment for a pipe bowl, pipe stem, cigarette holder, or cigar holder, or the like, for the purpose of draining off and absorbing any liquid which may accumulate in the smoke passages either from the combustion of the charge of tobacco or from the drainage of saliva, so that the pipe bowl and stem or the like will remain pure, and clean, and free from tars or other foul accumulations which not only tend to occasion disagreeable odors and irritations but result in the deposit and accumulation of residue which tends to choke up the smoke passages.

The device is so designed that it may be readily attached to or removed from pipe or cigarette holders of ordinary construction and may be readily opened up for cleaning or for the introduction of wads of cotton or similar absorbent materials which may be impregnated with chemicals for the purpose not only of absorbing liquid occasioned by drainage but also for the purpose of releasing vapors which tend to freshen and moisten the smoke so that it will not tend to dry out or irritate the membranes of the mouth, nose, or throat.

Further objects and details will appear from the description of the invention in conjunction with the accompanying drawing, wherein,

Figure 1 is a side elevation of the attachment embodying features of the present invention;

Fig. 2 is a sectional elevation of a pipe showing the attachment suspended from the neck of the bowl;

Fig. 3 is a similar view of a pipe stem showing the attachment suspended therefrom;

Fig. 4 is a similar view showing the attachment applied to a cigarette holder;

Fig. 5 is a cross-sectional view taken on line 5—5 of Fig. 2; and

Fig. 6 is a front elevation of the connecting plug which secures the attachment to the pipe neck, stem, or the like.

The attachment of the present invention is in the form of a cylindrical receptacle afforded by an open ended tube 10 provided at each end with threads to receive shouldered closing caps 11 which are preferably knurled as at 12 to readily permit the same to be unscrewed for the purpose of removal to permit the interior to be cleaned or reloaded with fibrous plugs 13 and 14 of cotton or the like. The plug 13 which occupies the forward position may be impregnated with hygroscopic chemical ingredients adapted to abstract liquid from the smoke and to assist in the absorption of liquids draining down from the smoke

passage while the rear plug 14 may be impregnated with a chemical ingredient adapted to give off vapors adapted to moisten and sweeten the smoke sufficiently so that it will not tend to cause dryness or irritation of the mouth or throat, or lungs, thereby tending to relieve congestion occasioned by excessive smoking or by the use of excessively dry or strong tobacco.

The tube 10 closed by the caps at each end, is carried by the neck or stem of a pipe or cigarette holder, as the case may be, by the provision of an attaching plug 15 which is formed to provide a medial disc-shaped body portion 16, a lower nipple 17, and an upper nipple 18. The lower nipple at its base is provided with threads 19, and the upper nipple at its base is provided with threads 20. The lower nipple is entered through an aperture 21 in the wall of the tubular receptacle 10 to permit the threads 19 to engage the wall which, when the parts are screwed together, will abut against the disc-shaped body 16, thereby bringing the lower end of the nipple 17 to a point about half-way above the floor or lower wall of the receptacle. Similarly the upper nipple is entered through a threaded aperture 22 which may be formed within the neck 23 of a pipe bowl, as in Fig. 2, or within the wall of a pipe stem 24, as in Fig. 3, or within a cigar or cigarette holder 25, as in Fig. 4. The upper nipple is of a length to extend through the smoke passage 26, 26a, or 26b, as the case may be.

The lower nipple is provided with a notch 27, and the upper nipple with a similar notch 28, and with the parts properly assembled, the notches 27 and 28 will provide passageways extending longitudinally of the tubular receptacle and the smoke passage respectively. The two passages are connected by a central duct 29 which affords a passageway for the drainage of liquid and also for the circulation of air and smoke into and out of the chamber within the receptacle 10. As will appear from Fig. 5, the side wall surfaces of the upper nipple extend upwardly through the side walls of the smoke passage to an elevation well above the base of the notch 28 which lies flush with the floor of the smoke passage, forming on each side a partial barrier of substantial height serving to retard the passage of liquid and other matter which otherwise might be drawn through the stem past the nipple. By this means a substantial portion of the liquid and other matter undergoing movement through the smoke passage is diverted inwardly through the notch and down through the vertical duct 29 into the chambered attachment,

In use, the suction through the stem of the pipe or the like will serve not only to suck smoke into the smoke passages but also to exhaust air from the receptacle which will tend to cause a portion of the smoke to circulate downwardly through the plug and into the receptacle where it will be freshened and sweetened by the vapors released from the impregnated fibrous plug while at the same time any excess of moisture, if any, in the smoke, or liquid which might otherwise tend to accumulate in the passages will be drained into the receptacle and absorbed by the fibrous wadding therein contained. Furthermore, any saliva tending to flow down from the mouth of the smoker during intervals between puffs will likewise tend to drain into the receptacle which occupies the lowermost level, so that the pipe at all times will be relieved from any accumulation of moisture or gummy or tarry materials occasioned by the condensation thereof which would otherwise tend to befoul the bowl and smoke passages.

It will, of course, be necessary to occasionally clean the receptacle and to renew the wadding therein contained, and this may easily be done by unscrewing and removing the screw-gaps 11 at each end of the receptacle which thus affords ready access to the interior to permit the same to be swabbed by a pipe cleaner or the like, or if desired, the receptacle can be easily unscrewed from the lower end of the plug which will permit thorough cleaning of every portion thereof. Likewise, if desired, the entire attachment can be readily removed from the pipe stem or the like to which it is secured to permit thorough cleaning of the smoke passages, which, however, will not be necessary at frequent intervals since the notch in the upper nipple which aligns with the smoke passage will permit the pipe cleaner or the like to be readily run through the smoke passage from end to end.

The device is one which may be readily attached to any pipe of conventional design or to a pipe stem or cigarette holder by merely boring and threading a hole therein to receive the threads of the upper nipple without further change or modification in structure. The device

is extremely simple in construction and is much superior in operation to devices intended to effect a similar result which require an interior reformation of the smoke passages thereby necessitating the formation of interior obstructions which often require frequent cleaning and, if befouled to any substantial degree, will render the pipe or the like unfit for use.

I claim:

10 In combination with a smoking device having a stem provided with a smoke passage extending longitudinally therethrough, a chambered attachment of tube-like horizontally elongated formation underlying and parallel with the adjacent portion of the stem and provided at each end with a removable plug affording access to the interior, a single vertically extending connecting plug with a relatively enlarged body and with oppositely extending upper and lower nipples 20 slotted through their ends and threaded at their bases, and the plug having a vertical passage therethrough terminating in the bases of the slots, the upper nipple having its base threaded transversely through the lower wall of an intermediate portion of the stem, and the lower nipple having its base threaded through the middle of the upper wall of the attachment with the upper and lower faces of the enlarged plug-body 30 in contact respectively with the exterior lower wall of the stem and the exterior upper wall of the attachment to hold the attachment in rigidly suspended substantially parallel relation with the adjacent portion of the stem and with 35 the slot of the upper nipple extending longitudinally of the interior of the smoke passage, and the side walls of said slotted nipple above the base of the slot being in contact with the walls of the smoke passage to serve as a partial barrier 40 to the flow of liquid along the smoke passage for diversion of the same through the vertical passage through the nipple to afford drainage into the chambered attachment and a wadding of absorbent material inserted within the chambered 45 attachment.

MAURICE BEN BRAND.
